United States Patent Office.

A. B. SHARP, OF PAINCOURTVILLE, LOUISIANA.

Letters Patent No. 73,054, dated January 7, 1868.

IMPROVEMENT IN DEFECATING CANE-JUICE.

The Schedule referred to in these Letters Patent and making part of the same.

TO ALL WHOM IT MAY CONCERN:

Be it known that I, A. B. SHARP, of Paincourtville, in the parish of Assumption, and State of Louisiana, have invented a certain new and useful Improvement in Apparatus for Defecating Cane-Juice, by which I am enabled to purify the fumes of sulphur, before said fumes enter the cane-juice, more thoroughly than has ever heretofore been done; and I do hereby declare the following to be a full, clear, and exact description of the same, reference being had to the annexed drawings, making a part of this specification.

It is well known to all who are conversant with the subject, that whilst, in the defecation or clarification of cane-juice, no agent is so effective and economic in its application as the fumes of sulphur, the process does not still produce results that are entirely satisfactory or complete, in consequence of the presence of impurities in the said fumes, that are absorbed by or taken up by the juice, as the fumes pass through it, to the permanent injury of the said juice, or of the sugar into which it is subsequently transformed, whilst the sulphurous gas, by reason of its more volatile nature, passes off without leaving a trace of its poisonous properties behind. It is also well known that if the fumes of sulphur be brought into contact with water, it is purified in precise proportion to the extent of such contact; and that hence, in all the more modern apparatus for clarifying cane-juice, a cistern to contain water has been introduced, through which the fumes are made to pass, before reaching the juice, with the view to their purification. But in all existing arrangements the effects are very incomplete, because the contact between the fumes and the water is only partial, being limited, in fact, to those portions of the former that touch upon the surface of the latter, which rests quiescent in the lower part of the cistern, whilst the fumes pass through the upper part thereof on their way to the cane-juice.

My invention provides a means of so agitating the water that all parts of the passing fumes are brought into contact therewith; and hence it secures the perfect cleansing of the same, and as a necessary corollary thereof, a subsequent perfect depuration of the cane-juice. In a word, my invention consists of a supplemental or additional chamber, annexed to the juice-receiver, to contain and agitate the water through which the fumes of the sulphur pass on their way into said receiver to purify said fumes. But my invention will be better understood by referring to the drawings, in which—

A represents a cane-juice receiver, or mixing-cylinder, or whatever else it may be called, as it appears externally, and B, my improvement, in the form of a somewhat larger cylinder, with a part of it broken away in order to show the partition or diaphragm C, which separates it from the juice-cylinder. B ought to be about one-third the length of A, and although I prefer it should have a greater diameter than A, it may manifestly be of the same size, if it be deemed desirable to have it so. At the end, D, my improvement may be closed in the same manner as Patterson closes his cylinder, or in any other convenient and suitable manner. It is separated in this form from the receiver A by the diaphragm C, which, it will be perceived, has a circular opening, a, in its centre. This opening a is made large enough to allow of the passage through it of the shaft, on which the two cylinders revolve and are sustained, as well as of a conduit-pipe for the cane-juice, which pipe can be placed more conveniently on the outside of the cylinder, so as to enter the same near the diaphragm C. Neither the pipe for the cane-juice, nor the shaft above spoken of, is shown on the drawings, nor any means for agitating the water within the cylinder B, for none of these things constitute any part of my invention. It will be readily understood, without the aid of illustration on the drawings, that the shaft is supported at both its ends, outside the cylinders, by journals, and that if it require intermediate support between its ends, such support may easily be introduced at any point by means of a central collar encircling said shaft, that is kept in place and sustained by arms projecting from said collar, and securely attached to the inner surface of the cylinder within which the support needs to be given. It will also be understood that the conduit for the cane-juice must be a pipe that, passing through water-cylinder B, terminates just past diaphragm C, so as to precipitate said juice very near the same, in order thus to insure the longest possible retention of it within cylinder A, and the consequent greatest possible action upon it by the purified fumes before it escapes, clarified thereby, at the end E of said cylinder, through a proper opening made for the purpose, to be further treated and converted into sugar.

The means I employ for producing a sufficient agitation or disturbance of the water to insure a proximate contact of every portion of the fumes of sulphur, may be similar to those employed by Patterson, in his cylinder A; that is to say, the means may consist of a series of thin flanches or ledges, which, attached to the inner

surface of cylinder B, and longitudinally therefrom, project inwardly for several inches towards the centre of the cylinder. These flanches, in the revolution of the cylinders, will alternately lift a portion of the water and pour it back again, and thus they will keep up a continual agitation thereof, which will be more or less extended accordingly as the flanches are placed near each other or further apart. If it be found expedient to make the cylinders A B stationary, and instead of the flanches or shafts, I have just described, to employ revolving beaters for breaking and stirring the water, it can easily be done; but in such case it is obvious that the pipe for conveying the cane-juice could not pass through the centre of the cylinder B, as in the first case, for it would prevent the revolution of the said beaters. It would not be difficult, indeed, to use both the projecting ledges and revolving beaters, since all that would be required in such case would be to leave a sufficient space between the ends of the beaters and the ends of the ledges to permit the juice-pipe to be conducted through the same, which might readily be done by bending it, or by letting the pipe enter from the outside. The water contained in cylinder B must never be allowed to flow into A, and to prevent this, water-valves, for preserving the water at a given point below opening α , in diaphragm C, must be provided in the cover or head of the cylinder at D, which will permit the water to escape whenever it attains the prescribed height. The fumes of sulphur are thrown into cylinder B, at the end D, by any usual or proper means, and no particular plan or appliance for doing this need herein be given.

The operation of my invention is as follows, to wit: The cylinders being set in motion, and the fumes of sulphur, the supply of water, which, as in the case of the fumes, may be introduced by any proper means, and the cane-juice being turned within the cylinders, the revolution of the latter agitates the water in cylinder B by means of the projecting flanches, as before described, and insomuch as the fumes of sulphur pass through said cylinder, and is thus brought into contact with the water, it is at once freed of all extraneous acid or other matter, and so purified before it enters into cylinder A, or can act upon the cane-juice therein contained.

My invention is of great importance and value, as has been demonstrated by experiment, not only in respect of the beneficial effects produced by it in the manufacture and refining of sugar, but also because it is simple, and can be made at less cost than any other contrivance looking to the accomplishment of the same end that is now in existence.

Having thus described my invention, what I claim, and desire to secure by Letters Patent, is—

The supplemental or additional revolving cylindrical water-cistern B, when constructed and operating in connecting with Patterson's cylinder A, or any other cylinder substantially the same, and specially employed for purifying the fumes of sulphur to be subsequently used in the defecation of cane-juice, as set forth.

A. B. SHARP.
